UNITED STATES PATENT OFFICE.

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE.

TRAVELING GRATE.

Application filed August 3, 1923. Serial No. 655,416.

This invention relates to traveling grates, and is particularly useful in connection with that type of traveling grate known as a chain grate stoker mechanism.

5 In the chain grate type of stokers, the grate is composed of an endless chain or belt, to the top of which the green coal is supplied and carried into the furnace or combustion chamber, the chain being driven by sprockets or the like. The grates, which 10 may vary in width, are composed of a plurality of links secured together in chain form by means of pintles. In service, there is a tendency for the links to separate, unduly 15 increasing the size of the openings or spaces between links. Heretofore yieldable means have been provided at each side of the grate to force the links together as a set, but this arrangement has not proven practical, particularly 20 since developments in modern practice have been such as to necessitate an increase in the width of the grates.

One of the primary objects of my invention is to provide a simple and effective 25 means whereby the links are maintained in proper relation with respect to each other transversely of the chain.

Still another object of the invention is the provision of means whereby it is possible to 30 increase the width of the chain grates considerably in excess of the maximum width now possible in standard practice.

The foregoing, together with such other objects as may hereinafter appear, or are incident to my invention, I obtain by means of a construction which I have illustrated in preferred form in the accompanying drawings, wherein:

Fig. 1 is a somewhat diagrammatic side 40 elevation of a chain grate stoker embodying my invention;

Fig. 2 is a plan view partly diagrammatic of a portion of the chain grate, on a larger scale, taken as indicated by the line 2—2 of 45 Fig. 1; and

Fig. 3 is a sectional view illustrating certain of the links in side elevation.

Referring now particularly to Fig. 1, the reference character A denotes the furnace or combustion chamber into the firing or charging opening 7 of which, the chain grate stoker B extends. The coal is fed onto the grate through the hopper and feed mechanism C. The grate consists of the endless

chain 8, driven at one end by the sprocket 55 mechanism 9 and riding over the drum or roller 10 at the other end. In its upper traverse, the chain is supported by the roller 11 and the rollers 12 which will be further described. 60

At this point attention is called to the fact that the various supporting devices for the grate are such that the top of the grate, in general, is curved, i. e., rises from the front to the middle and falls away from the middle 65 toward the rear.

Referring now to Figs. 2 and 3, it will be seen that the chain is composed of links 13, such as shown, for example, in my copending application Serial No. 635,045, filed 70 April 27, 1923, such links being arranged in rows transversely of the chain, the links of one row being staggered with respect to the links of the adjacent rows. Each link has a pair of pintle-receiving slots 14, inclining 75 downwardly and inwardly toward each other. The links are assembled on and are removed or detached from the pintles 15 in the manner described in the said application; that is, by bringing the link involved 80 over the usual drum at one end of the grate, and drawing together the adjacent links in an adjacent row, or vice-versa.

This form of link, as well as other forms of links in use, has the tendency, previously 85 described, of separating transversely of the grate under service conditions. To overcome this it will be seen that I have angularly disposed the rollers 12, i. e., they extend at slight angles from a right angle to 90 the path of travel of the grate. It will be noted that these rollers are alternately oppositely inclined, and that adjacent rollers have collars or flanges 17 at opposite ends.

Considering now the left-hand roller of 95 Fig. 2, the effect of its inclination is to tend to cause the links thereover to move toward the far side of the grate. Its flange 17, however, prevents or limits any lateral displacement of the chain, and thus the result is that 100 the links are held or pressed together. The next roller has a tendency to cause the links to move toward the other side of the grate, as described; the third roller has the same effect as the first roller; and so on from 105 roller to roller. Thus the tendency of alternate rollers to shift the links to one side of the grate is opposed and neutralized by the

equal and opposite tendency of the other rollers. The net effect of the rollers is such as to prevent the links from separating transversely of the chain, thus preventing the opening up of objectionable gaps with an area over and above that which is normally intended to exist between links. The advantages of this, in operation, will readily be appreciated by those skilled in the art.

10 The rollers are journaled in bearings 12^a which are free to slide in a direction transverse of the grate. As a result, while the links over a roller are pressed together toward one end thereof, the roller as a whole is free to shift in an opposite direction under the general pull on the grate, so that there is no net lateral displacement of the grate at any point.

20 The general principle upon which the invention proceeds is that the supporting members or surfaces are such that, considering any given point thereof, such point, in moving, will travel toward a side of the grate during the interval of contact, while at the same time there is in reality no lateral displacement of the grate as a whole. It will be obvious that this principle may be realized by other than the specific arrangement shown.

30 As heretofore pointed out, the arrangement is so effective in operation that it is possible to increase the width of the chain grates almost without limit, without running into the difficulty of opening up undesirable gaps between the links.

What I claim is:

1. The combination with a traveling grate composed of a plurality of elements, of a supporting surface for engaging them moving toward a side of the grate.
2. The combination with a traveling grate composed of a plurality of elements, of a plurality of supporting surfaces for engaging them, alternate surfaces moving towards

opposite sides of the grate, during operation. 45

3. The combination with a traveling grate composed of a plurality of elements of a support therefor tending to cause movement of the elements toward a side of the grate.

4. The combination with a traveling grate 50 composed of a plurality of elements, of a plurality of supports tending to cause movement of the elements alternately toward opposite sides of the grate.

5. The combination with a traveling grate 55 composed of a plurality of elements, of a roller for engaging them extending across the line of movement of the grate and at an inclination thereto.

6. The combination with a traveling grate 60 composed of a plurality of elements, of a plurality of rollers for engaging them extending across the line of movement of the grate and alternately, oppositely inclined from a perpendicular thereto. 65

7. The combination with a traveling grate composed of a plurality of elements, of a plurality of rollers for engaging them extending across the line of movement of the grate, and alternately, oppositely inclined 70 from a perpendicular thereto, together with means preventing displacement of the grate.

8. The combination with a traveling grate composed of a plurality of elements, of a plurality of rollers for engaging them extending across the line of movement of the grate, and alternately, oppositely inclined 75 from a perpendicular thereto, together with means on the rollers preventing displacement of the grate. 80

9. A chain grate composed of a plurality of links, in combination with a roller for engaging them, said roller being set at an oblique angle to the line of movement of the grate. 85

In testimony whereof, I have hereunto signed my name.

WILFRED R. WOOD.
